(57) **CLAIM**

The ornamental design for “packaging for cartridges for use with a vaporization device,” as shown and described.

DESCRIPTION

FIG. 1 is a perspective view of packaging for cartridges for use with a vaporization device; and,

FIG. 2 is a top view of the packaging of FIG. 1.
In the drawings, the broken lines represent unclaimed subject matter and form no part of the claimed design.

1 Claim, 2 Drawing Sheets
